Primary Examiner — Omeed Agilee

Assistant Examiner — Eric Eldone Tormanen

(57) **CLAIM**

The ornamental design for a acne patch, as shown and described.

DESCRIPTION

FIG. 1 is a front perspective view of a acne patch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and,

FIG. 10 is an enlarged detail view of area 10 in FIG. 3.

The dot-dash broken lines depict the bounds of the enlarged views that form no part of the claimed design.

1 Claim, 10 Drawing Sheets
